UNITED STATES PATENT OFFICE

2,467,865

HAMMER FOR IMPACT PULVERIZER

Forrest E. Smith, Asheville, N. C.

Application May 3, 1944, Serial No. 533,851

1 Claim. (Cl. 241—197)

1

The present invention relates generally to improvements in rotary impact crushers or pulverizers, and has particular reference to improvements in the revolving hammers adapted for use therein.

Pulverizing hammers of the type disclosed in my prior Patent No. 2,152,332 are provided with a replaceable wear tip which is reversibly and removably connected to the outer end of the hammer arm, and which has oppositely disposed impact faces formed with marginal corners or edges that extend transversely of the path of movement for impact with the incoming material to be pulverized. These impact corners or edges are adapted to be disposed individually in a leading or working position at the extreme outer end of the hammer upon securing the tip thereto in different selective positions of assembly. When the arm and the tip are symmetrically arranged relative to the longitudinal center line of the hammer, as has been the practice heretofore, the two outermost impact edges are equidistant from the axis of revolution and are located respectively in leading and trailing positions. Consequently, as wear occurs in use, the leading edge will recede and after a certain amount of such recession, the trailing edge will also come into contact with the material being pulverized and hence into the line of wear. It is, therefore, desirable, in order to obtain full and uniform wear on all impact edges of the replaceable tip, that the tip be reversed frequently and at proper times back and forth into its different selective positions on the hammer arm. Such reversal of necessity requires frequent attention, and involves inconvenience and loss of production time.

The primary object of the present invention is to provide a novel pulverizing hammer, having a plurality of selectively available impact corners or edges which will be efficient and comparatively long-lived in use, and which in particular will permit each of the impact edges to be worn out completely.

Another object is to provide a new and improved pulverizing hammer having a reversible tip which is removably connected to the hammer arm in such a manner that when any one of a plurality of impact corners or edges is located for use in working position, it alone will be subject to wear until completely worn out, while the other edge or edges will be spaced inwardly away from the line of wear.

A further object is to provide a novel pulverizing hammer having an arm and a replaceable tip in which the tip is so mounted that the center of

2

gravity is located in advance of the center line of the arm, whereby to project one impact edge outwardly radially beyond the other edge or edges.

A general object is to provide a new and improved pulverizer hammer which is simple and inexpensive to manufacture, which permits of a maximum amount of wear with a minimum loss of scrap metal when the tip is replaced, and which requires little attention in use and adjustment of the tip only after each edge is completely worn out.

Other objects and advantages will become apparent as the description proceeds.

In the accompanying drawings,

15 Figure 1 is a side elevational view of an impact hammer with a four-corner tip embodying the features of my invention.

Fig. 2 is an enlarged perspective view illustrating the arm and tip of the hammer in disassembled relation.

Fig. 3 is a side elevational view of a modified form of hammer with a two-corner tip.

Fig. 4 is a front face view of the hammer shown in Fig. 3.

25 Fig. 5 is a sectional view taken along the line 5—5 of Fig. 3.

Fig. 6 is a transverse vertical sectional view of a pulverizer provided with impact hammers embodying the features of my invention.

30 While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claim.

40 Referring more particularly to the drawings, impact hammers embodying the present invention are adapted for use in various types and kinds of crushers or pulverizers, and for purposes of illustration one form of hammer is shown in connection with a rotary pulverizer of conventional design (Fig. 6). The pulverizer comprises a casing 10 which is mounted on a base 11, and which has a feed inlet 12 at one side for the material, such as stone, to be crushed or pulverized. Suitably mounted in the casing 10 is a drive shaft 13 adapted to be connected to a source of power (not shown). Hammer suspension means is mounted on the shaft 13, and in the present instance comprises a plurality of axially spaced disks 14 (one shown) se-

cured in fixed relation to the shaft. A plurality of hammers 15, four in the present instance, are suitably secured in uniformly peripherally spaced relation to the disks 14 and project radially therefrom. The casing 10 is provided in the top portion with a liner plate 16 and in the bottom with a grate structure 17, conforming generally to the circle of revolution of the hammers 15.

It will be understood that in use the hammers are revolved at very high speeds. Hence, they are subjected to heavy centrifugal force and also to severe impact in reducing the material to be pulverized. Wear occurs at the outer leading edges of the hammer tips, and necessitates frequent replacement of the hammers.

The primary feature of the present invention resides in the provision of an impact hammer having a replaceable tip with a plurality of impact corners or edges which can be easily and quickly reversed to permit successive use of all the impact edges before requiring replacement, and which in different positions of adjustment, will subject only the active edge to wear through contact with the material being pulverized.

Referring first to the form of Figs. 1 and 2, the hammer constituting one exemplary embodiment of the invention comprises a pivotal suspension member which may be of any suitable type, and which is shown as a flat-sided hammer arm 18 adapted to be pivotally connected at one end to the disks 14 for swinging movement. In the present instance, the inner end of the arm 18 is formed with an opening 19 adapted to receive a supporting shaft 20 anchored to the disks 14 and extending through the intervening space in parallel relation to the shaft 13. In operation, centrifugal force will cause the arm 18 normally to occupy a generally radial position with reference to the axis of revolution.

A replaceable wear tip 21 is reversibly secured to the other or outer end of the arm 18, and is removably connected thereto by a strong joint. The tip 21 is provided with a plurality of spaced impact edges which extend transversely of the path of revolution, and which are adapted to be located singly in active position by selective reversal of the tip on the arm 18. In the particular form shown, the tip 21 is generally rectangular in cross section and is formed with front and rear impact faces 22 and 23. The four transverse corners A, B, C and D, which extend along and define the margins of the impact faces 22 and 23, constitute the impact edges. These edges are comparatively sharp at the start, but as they wear in use will recede and become rounded along the line of wear 24. Preferably, the impact faces 22 and 23 are slightly hollow V-shaped.

The tip 21 is supported on the arm 18 in such a manner that only one of the impact edges at a time will be located in active or working position to strike the material being pulverized. As a result, the inactive edges will be maintained out of contact with the material, and wear will be confined to the active edge.

Selective location of the impact edges singly in active position is accomplished by mounting the tip 21 on the front or leading side of the arm 18, whereby the center of gravity H of the hammer is located on a radial line h—h through the axes of the shafts 13 and 20 eccentrically to and in advance of the longitudinal center line a—a and center of gravity A of the arm 18, and trailing the center of gravity T of the tip 21 on the radial line t—t through the axis of the shaft 20. More particularly, one or the other of the impact faces 22

and 23 is seated against a complementary mounting surface 25 on the front of a cross head 26 integral with the outer end of the arm 18. With the tip 21 so mounted, two of the impact edges, for example the edges A and B, are located in a leading position, and the other two edges, for example the edges C and D, are located in a trailing position. The outermost leading edge, for example the edge A, is disposed in active position to strike the material being pulverized, and in use is subject to wear down to the line of wear 24. By reason of the eccentricity of the center of gravity, the four-corner tip 21 will occupy a forwardly and outwardly inclined position so that the outermost trailing edge, for example the edge D, is caused to move through a reduced circle of revolution well within the line 24 and, therefore, out of striking contact with the material. Obviously, the innermost impact edges B and C are spaced radially inwardly from the outermost edges A and C and, therefore, are also out of striking contact with the material.

The joint for positively locating and connecting the tip 21 in different selective positions to the arm 18 comprises two spaced keys or lugs 27 projecting forwardly from opposite side areas of the mounting surface 25, and adapted to be received in complementary recesses or grooves formed in opposite sides of the tip. The grooves 28 open to both impact faces 22 and 23 so that the lugs 27 will engage in one end or the other, thereby permitting reversal of the tip front for rear to locate either the edges A and B or the edges C and D in the foremost or leading position. The grooves also are located symmetrically across the sides of the tip 21 so that the latter can be reversed side for side to locate either the edges A and D or B and C in the outermost position. Preferably, the lugs 27 are tapered, and the opposite ends of the grooves 28 are correspondingly flared to obtain close wedge engagement.

As an additional locating and interlocking means, the head 26 is provided with an intermediate square lug or projection 29 between the lugs 27 and adapted to be received in either of two complementary openings 30 which are formed centrally in the respective impact faces 22 and 23 and separated by an intermediate wall or web 31. To secure the tip in position of assembly, a bolt 32 is adapted to be inserted through a hole 33 in the web 31 and an aligned bore 34 opening through the square lug 29 and the head 26, and to be tightened by a nut threaded thereon against the rear face of the arm 18.

In operation, and assuming that the tip 21 is initially secured in position of assembly with one of the impact edges, for example the edge A, disposed in the outermost leading position for striking engagement with the material being pulverized, centrifugal force will cause the tip to assume a position inclined to the radius of revolution, with the active edge A describing a maximum circle of revolution. The other impact edges B, C, and D will describe lesser circles of revolution, and hence remain out of striking contact with the material. Upon continued use, the edge A will be worn away down to the line 24, and when the edge has been completely worn down, the tip 21 can be reversed, for example side for side, to dispose the other impact edge B of the face 22 in active position. When the second edge B has been completely worn down, the tip can be reversed front for rear to dispose the edge C in active position, and finally upon reversal side for

side the edge D can be disposed in active position.

Figs. 3, 4 and 5 illustrate a modified form of the invention having a two-corner replaceable tip 21^a. The construction is generally similar to that of the hammer with the four-corner tip, and corresponding parts thereof are identified by the same reference numerals as in the first form, plus the letter *a*. In this form, the tip 21^a has a rear surface 23^a adapted to seat against the front surface 25^a of the head 26^a, and has only one impact face 22^a with transverse marginal corners or impact edges E and F. The surfaces 23^a and 25^a are flat and located substantially in an axial plane through the shaft 20. The tip 21^a is not reversible front for rear and, hence, the recesses 28^a do not extend to the face 22^a. The lugs 27^a of the joint are tapered on such an angle that the outermost inclined sides thereof are substantially parallel to the line of wear 24^a, thereby making available a maximum amount of stock to be worn away at each corner. In this form, as in the form of Figs. 1 and 6, the tip 21^a has a center of gravity T' on a radial line *t*'—*t*' through the axis of the hole 19^a, and the arm 18^a has a center of gravity A' on a radial line *a*'—*a*' also through the axis of the hole 19^a, and the hammer including the arm 18^a and eccentrically mounted tip 21^a has a center of gravity H' intermediate the centers of gravity T' and A' on a radial line *h*'—*h*' extending through the axes of the opening 19^a and the shaft 13 when the hammer is subjected to centrifugal force.

It will be evident that I have provided a new and improved impact hammer which has a plurality of impact corners or edges adapted to be used one after another until completely worn out, and in which none of the corners excepting the one located in active position is subject to wear. As a result, all corners of the hammer can be fully worn down in performing useful work and to leave a minimum of stock to be discarded when the tip is replaced. Frequent reversal of the tip is unnecessary so that undue loss of production time is avoided.

I claim as my invention:

An impact hammer for rotary pulverizers comprising, in combination, a hammer arm adapted to be supported at one end and having a cross head on the other end with a mounting surface on the leading side, two forwardly projecting

wedge lugs extending in spaced relation from opposite ends of said surface, and an intermediate lug extending forwardly from said surface between said wedge lugs, a four-sided hammer tip having front and rear faces adapted to be seated directly against said surface and having four transverse corners defining impact edges at the inner and outer margins of said faces, said tip being formed in opposite ends with transverse grooves flared outwardly in each direction from an intermediate point and adapted to interfit selectively with said wedge lugs and being formed in said faces with openings separated by an intermediate web and adapted to interfit and receive said intermediate lug, said tip being reversible on said surface side for side and front for rear to present any one of said four corners in an outermost forward working position, and being located in advance of and spaced from the center line of said arm, whereby to cause the trailing outermost corner to have a lesser circle of revolution than the forward outermost corner, and a clamping bolt adapted to be extended through said web and said intermediate lug for removably securing said tip to said head in selected position of adjustment.
